(57) **CLAIM**

The ornamental design for a multi directional input apparatus, as shown and described.

DESCRIPTION

FIG. 1 is a front elevational view of the multi directional input apparatus showing my new design;

FIG. 2 is a reduced scale top plan view thereof;

FIG. 3 is a reduced scale bottom plan view thereof;

FIG. 4 is a right side elevational view thereof;

FIG. 5 is a left side elevational view thereof;

FIG. 6 is a rear elevational view thereof;

FIG. 7 is a sectional view thereof; taken along line 7—7 of FIG. 2; and,

FIG. 8 is a perspective view from the right front quarter.
